HENRY BROBERG, OF WARM SPRINGS, MONTANA.

CLAMP FOR CUE-TIPS.

1,131,111.

Specification of Letters Patent.

Patented Mar. 9, 1915.

Application filed January 22, 1914. Serial No. 813,795.

To all whom it may concern:

Be it known that I, HENRY BROBERG, a citizen of the United States, residing at Warm Springs, in the county of Deer Lodge and State of Montana, have invented certain new and useful Improvements in Clamps for Cue-Tips, of which the following is a specification.

This invention relates to a clamp which is intended to be used for holding the tip upon the ends of a cue while the cement with which the tip is held in place is hardening.

One of the objects of the invention is to provide a clamp which is so constructed that it will be securely held about a cue of any size, and to so construct the clamp that it will not slip out of place while the cement is hardening.

Another object of the invention is to so construct the clamp that it may be formed from a sheet metal blank which is bent to assume the proper shape to form the complete clamp.

Another object of the invention is to so construct the clamp that when the turn screw is rotated to bring the cup into engagement with the cue tip, the clamp will not be moved longitudinally upon the cue.

This invention is illustrated in the accompanying drawings wherein—

Figure 1 is a view in elevation showing the clamp applied to a cue with the engaging cup shown in section; Fig. 2 is a transverse sectional view taken along the line 2—2 of Fig. 1; Fig. 3 is a view similar to Fig. 1 with the clamp shown in longitudinal section; Fig. 4 is a view showing the clamp and cue in elevation, the view being taken at right angles to the view shown in Fig. 1.

The cue 10 is of the ordinary construction and is provided with a tip 11 which is formed of any suitable material such as leather and connected with the end of the cue by means of cement or the like. The clamp is formed from a blank of resilient sheet metal which is bent to form a housing having a bridge 12 and side arms 13 and 14. In the center of the bridge 12 there is provided a bearing 15 provided with an opening from the edges of which there extends an internally threaded sleeve or collar 16. This sleeve or collar 16 extends inwardly as shown at Fig. 3 and carries a threaded stem or screw 17, the outer end of which is formed into an enlarged head 18. This head 18 is provided so that the stem 17 may be readily rotated and move the cup 19 into engagement with the cue tip 11. This cup 19 is loosely mounted upon the reduced neck 20 of the stem 17 and is held in place by the head 21 which fits into a socket formed in the cup. It will thus be seen that after the cup has been brought into engagement with the cue tip, the cup will not rotate, but will be pressed tightly against the cue tip when the stem is rotated.

The arms 13 and 14 have their free-end portions 22 brought toward each other as shown at 23 and then carried parallel as clearly shown in Fig. 1. The parallel end portions of the arms are curved to cause the arms to form jaws which will fit tightly about the cue when the turn screws 24 are tightened. The turn screws 24 pass through bearings 25 and 26 which are formed in the wings 27 and 28 extending laterally from the jaws 22. The turn screws 24 are rotatably mounted in the bearings 25 and pass through internally-threaded sleeves or collars 29 carried by the bearings 26, and it will thus be seen that when the turn screws are rotated, the two jaws may be clamped tightly about the cue. The bearings 26 are formed very similar to the bearings 15 and the bearings 25 are also formed very similar to the bearings 15 with the exception that the bearings 25 are not provided with internally-threaded sleeves.

The operation of this device will be readily understood from an inspection of Figs. 1, 2, and 3. After the cue tip 11 has been placed against the end of the cue, the clamp will be placed upon the cue with the cue extending between the jaws 22. The turn screws will then be tightened to securely hold the clamp in place and the stem or turn screw 17 will then be rotated to bring the cup 19 into engagement with the cue tip. This cue tip will be compressed as shown at Fig. 3 and held in this position until the cement has completed drying, at which time the clamp can be removed and the cue tip will be securely held in place. By having the cup concaved as shown in Figs. 1 and 3 the tip when compressed will be prevented from moving transversely and will thus be held in the center of the cue end and prevented from being secured to the cue with one portion of the cup extending beyond the side of the cue.

I have thus provided a cue tip clamp

which can be easily and quickly put in place and which will securely hold the tip in place while the cement is drying. It should also be noted that by having this clamp 5 formed of resilient sheet metal, when the turn screws 24 are tightened, the resiliency will cause a binding engagement between the threads of the turn screw and sleeves 29 and thus prevent any danger of the turn 10 screws working loose and permitting the clamp to move longitudinally toward the end of the cue and thus release the pressure upon the tip applied by the turn screw 17.

What is claimed:

15 A clamp comprising a body portion formed from a blank of resilient material bent intermediate its length to form a bridge having a threaded bearing, the end portions of said blank extending from said 20 bridge to form arms extending in spaced re-

lation and having their end portions bent toward each other and then carried in spaced relation, the end portions of said arms being bent to form longitudinally extending jaws for receiving a cue, side wings 25 extending from said arms and provided with bearings, one set of said last mentioned bearings being threaded, set screws passing through said last mentioned bearings for moving said arms into clamping position, a 30 set screw passing through said first mentioned bearing, a tip engaging head carried by said set screw.

In testimony whereof I affix my signature in presence of two witnesses.

HENRY BROBERG.
